BOTTING APPARATUS

Martin O'Hare, Donora, Pa., assignor to The American Steel and Wire Company of New Jersey, a corporation of New Jersey

Application July 31, 1946, Serial No. 687,268

6 Claims. (Cl. 266—42)

1

This invention relates to botting apparatus for blast furnaces and the like.

The present invention has among its objects the provision of an improved botting apparatus wherein warpage of the bott rod supporting structure by heat from the furnace and molten cinder tapped therefrom is materially reduced.

This and other objects of the invention will be more readily apparent in the following description of a preferred embodiment of apparatus within the teaching of the invention.

Botting apparatus heretofore employed has included a bott for stopping the opening in the furnace cinder notch, a bott supporting rod on the forward end of which the bott is attached, and a structure supporting the bott and bott rod in line with the cinder notch and selectively advancing the bott into the cinder notch to stop the flow of cinder and retracting the bott to open the notch for the flow of cinder from the furnace. Typical of such prior apparatus is that shown and described in my Patent No. 1,841,202, issued January 12, 1932, on which the apparatus of the preferred embodiment of the present invention is an improvement. It is to be understood, however, that in its broader aspects some variations are possible and that the present invention is not limited to the structure of the preferred embodiment.

Prior to the present invention, which provides a liquid-cooled bott rod supporting mechanism, such structure required considerable maintenance to keep it in good operating condition. The means for supporting the bott rod and for allowing its reciprocation toward and from the furnace, generally termed the botting rigging, is subjected to very high temperatures because of its location in the immediate vicinity of the furnace and its cinder notch, and, in at least a portion of its travel, substantially above the cinder runner. The heat emitted from the furnace, the cinder notch, and the molten slag or cinder passing beneath the rigging caused warping to occur in prior botting rigging structures both in the framework carrying the bott rod and the supporting beams therefor. Such warpage obviously causes poor operation of the botting apparatus in that the bott rod is thrown out of alignment with the cinder notch opening in the furnace and the traveling frame tends to bind on the supporting beam or beams, due to warpage of both the frame and the beam or beams.

The apparatus of the present invention overcomes the above described difficulties arising from distortion of the botting rigging by its be-

2

coming unduly heated. Such result is accomplished, as above indicated, by the provision of liquid cooling means for the bott rod support and for the means for allowing movement of the rod to and from the cinder notch.

The invention will be more readily understood by reference to the accompanying drawings, in which:

Figure 1 is a view in side elevation of a preferred embodiment of the improved botting apparatus, the furnace in the vicinity of the cinder notch being shown in section;

Figure 2 is an enlarged view in side elevation of the botting apparatus shown in Figure 1;

Figure 3 is a view in plan of the botting apparatus and its attendant mechanism; and

Figure 4 is a view in vertical section of the supporting beam, the section being taken along the line IV—IV in Figure 2.

20 The blast furnace with which the botting apparatus of the invention is associated is indicated at 2, such furnace being provided with the customary bustle pipe 10° from which blast air is led to tuyères, of which one is shown at 1.

25 The furnace is provided with a cinder notch, generally indicated at 4, such notch being closed to the flow of cinder therethrough, except when the cinder is to be tapped, by bott 10, shown in Figures 1 and 2 in retracted position. The furnace is provided with columns 7, which aid in supporting the furnace walls and to which various furnace appurtenances, such as the blast pipes leading to the tuyères and the forward end of the bott supporting and reciprocating structure, are affixed.

30 The botting apparatus shown is generally similar to that disclosed in Patent No. 1,841,202, above referred to, in that it has a horizontal member 15, of generally I beam cross section, positioned above the cinder notch and in a vertical plane containing the axis of the cinder notch opening. Member 15, which provides a trackway upon which the bott rod supporting frame travels, is supported at its forward end by reason of its attachment to the transverse hollow member 5, which in turn rests upon brackets 6 attached to columns 7. Member 5 may be attached to beam 15 as by shackles 16 embracing member 5 and extending through the solid upper flanges of member 15. The rear end of member 15 is supported by vertical member 25 through the medium of bracket 27 attached thereto.

35 The bott 10 is supported on the forward end of bott rod 12, which is in the form of a pipe, rod 12 being joined to the bott rod supporting

frame or trolley by coupling 13. The bott rod supporting frame, which is made up of communicating pipes welded together as shown, will be further described below. Such frame is arranged to be supported from beam 15, and to travel therealong, by sets of opposed rollers 22 in suitable hanger members attached to the top of the frame. Rollers 22 engage and ride upon the top surface of the bottom flange of beam 15.

The bott rod supporting frame may be selectively advanced toward and retracted from the furnace by various known means, of which that employed in the botting apparatus disclosed in Patent No. 1,841,202 is one. Such mechanism comprises a flexible member 30' having opposed runs extending lengthwise of beam 15, member 30' being supported by the vertical idle pulley 40 adjacent the forward end of beam 15 and the horizontal idle pulley system 32 at the rear end of beam 15. From such latter pulley system member 30' passes to winding mechanism indicated generally at 42 in Figure 3. The winding mechanism is so constructed as to cause opposed runs of member 30' to travel in opposite directions lengthwise of beam 15, so that by attaching the bott rod supporting frame to one run of member 30', such as by connecting the rear hanger for rolls 22 to the lower run of member 30', as shown, rotation of the winding mechanism in one direction causes the frame to approach the furnace and rotation of the winding mechanism in the opposite direction causes the frame to be retracted from the furnace. The winding mechanism may, if desired, be provided with a counterweight device (not shown), such as disclosed in Patent No. 1,841,202, for causing the bott rod supporting frame to travel toward the furnace.

The beam 15, in accordance with the present invention, is of hollow construction to allow it to be cooled by liquid circulating through it under pressure. A preferred manner of making beam 15 is shown in Figure 4 wherein it is shown composed of parallel side pieces 16' and 16', which are of channel shape, the side pieces being joined in opposed relationship as shown by the longitudinal top and bottom closure members 3 and 3', respectively. Preferably members 3 and 3', are affixed to members 16' and 16' by continuous edge welds. The space enclosed within parts 3, 3', 16', and 16' constitutes a liquid coolant receiving space, into which cooling liquid is led through pipe 8 and from which the liquid is exhausted through pipe 30. As shown in Figure 3 pipe 8 is connected to one end of the hollow member 5 supporting the forward end of beam 15, the outlet pipe 9 from member 5 being connected to the forward end of the coolant space within beam 15. The supporting member 5, as well as beam 15, is thus liquid cooled.

The bott rod supporting frame or trolley is also cooled by liquid coolant flowing therethrough. Such frame, which is of generally rectangular shape, consists of a top pipe member 17, a parallel bottom pipe member 18, front and rear vertical pipe members 20 and 21, respectively, and a diagonal bracing pipe member 22. All such pipe members are connected to each other as shown, preferably by welding, so as to have intercommunicating passages therethrough. Coolant liquid for the bott 10 and bott rod 12 is led thereto through pipe 11, which connects with an internal pipe 14 which extends through bottom frame member 18 and bott rod or pipe 12 to a point adjacent the forward end of the hollow

bott 10. Preferably pipe 14 is positioned coaxially of members 18 and 12 by apertured spacer members (not shown) internally of such latter members and about pipe 14. Pipe 14 extends through cap 44 on the rear end of member 18, cap 44 forming a liquidtight connection with pipe 14.

Coolant liquid, led under pressure to pipe 11 by flexible hose 34 which is of sufficient length to allow full travel of the frame between its forward and rear limits, travels through pipe 14 until it is discharged from such pipe with bott 10. Thereupon such liquid travels back toward and into the frame in the space between pipe 14 and bott rod or pipe 12 and bottom frame member 18. Thence the coolant travels upwardly, in the directions indicated by the arrows in Figure 2, through members 19, 20, and 21 into member 17. Pipe 36, connected to the rear end of member 17, to which flexible hose 38 is connected, provides for the discharge of the heated coolant to a suitable sump.

The apparatus described has the advantage that the pipe lengths 17 through 21 together constitute a reservoir of coolant liquid of substantial capacity which constantly maintains a static head of pressure on the coolant in the rod 12, thus insuring more effective cooling thereof. Continued cooling is provided, furthermore, even should the supply of liquid to connection 34 be interrupted temporarily. This minimizes the likelihood that the bott 10 will be overheated and damaged.

Because of its cheapness and availability at a furnace such as a blast furnace, where it is employed for cooling the tuyères and various parts of the cinder notch, water makes an ideal liquid coolant for the liquid cooled members of the botting apparatus of the present invention. Such water may be introduced into the coolant receiving spaces of the apparatus at the pressures employed for the tuyère and cinder notch coolant water.

Having thus fully described a preferred embodiment of the improved botting apparatus of the present invention, I desire to claim as new the following:

1. In a botting apparatus for controlling flow through a discharge opening such as the cinder notch of a blast furnace, including a beam extending outwardly from the opening at a level thereabove, the improvement comprising a trolley reciprocable along said beam, said trolley being composed of tubular members, a tubular bott rod extending from said trolley and communicating with the interior of one of the tubular members thereof and coolant-liquid connections extending to said trolley.

2. In a botting apparatus for controlling flow through a discharge opening such as the cinder notch of a blast furnace, including a hollow beam extending outwardly from the opening at a level thereabove providing a track for a bott rod trolley, a hollow member extending transversely of said beam adjacent the inner end thereof and supporting the latter, coolant liquid connections extending to said beam and member, and an interconnection between a point adjacent the inner end of the beam and a point adjacent one end of said member.

3. In a botting apparatus for controlling flow through a discharge opening such as the cinder notch of a blast furnace, a hollow beam extending outwardly from the opening at a level thereabove, a trolley reciprocable along said beam, said trolley being composed of tubular

members, a tubular bott rod extending from said trolley and communicating with the interior of one of the tubular members thereof and coolant-liquid connections extending to said beam and trolley.

4. The apparatus defined by claim 1 characterized by said trolley including a bottom horizontal member and upright members, said bott rod being secured to said bottom member in alignment therewith and in communication with the interior thereof.

5. The apparatus defined by claim 4 characterized by a feed-in pipe extending through said bottom member and into said rod.

6. The apparatus defined by claim 1 characterized by said trolley including a rectangular frame composed of pipe lengths connected to-

gether and communicating with each other, thereby providing a reservoir of coolant liquid which maintains a static head of pressure on the interior of the rod.

MARTIN O'HARE.
